(57) **CLAIM**

The ornamental design of a fluid filtration device, as shown and described.

DESCRIPTION

FIG. 1 is a perspective view of a fluid filtration device according to the invention;

FIG. 2 is a bottom plan view of the fluid filtration device of FIG. 1;

FIG. 3 is a top plan view of the fluid filtration device of FIG. 1;

FIG. 4 is a first side elevation view of the fluid filtration device of FIG. 1;

FIG. 5 is a second side elevation view of the fluid filtration device of FIG. 1;

FIG. 6 is a front elevation view of the fluid filtration device of FIG. 1; and,

FIG. 7 is a rear elevation view of the fluid filtration device of FIG. 1.
